UNITED STATES PATENT OFFICE.

PAUL SCHNEIDER AND HENRY TRENKAMP, OF CLEVELAND, OHIO.

VAPOR-BURNER.

SPECIFICATION forming part of Letters Patent No. 251,738, dated January 3, 1882.

Application filed July 22, 1881. (Model.)

To all whom it may concern:

Be it known that we, PAUL SCHNEIDER and HENRY TRENKAMP, of Cleveland, in the county of Cuyahoga and State of Ohio, have invented 5 a certain new and Improved in Vapor-Burner; and we do hereby declare that the following is a full, clear, and complete description thereof.

The nature of this invention relates to a vapor-burner for gasoline-stoves. Said burner consists of a gas-generator situated directly below the combustion-chamber. Said chamber is put in communication with the generator by tubular conductors provided with a needle-valve. Within the combustion-chamber is a tubular cylinder, into which the gas for consumption is discharged, flowing therefrom over the top of the tubular cylinder into the combustion-chamber, as hereinafter more fully described, and illustrated by the accompanying drawings, 15 20 making a part of this specification, in which—

Figure 1 is an external side view of the burner above alluded to. Fig. 2 is a vertical transverse section. Fig. 3 is a detached view. Fig. 4 is a perspective view.

Like letters of reference refer to like parts in the several views.

As shown in the drawings, A represents a feed-pipe connecting the burner to an oil can or reservoir, constructed and arranged substantially in the same way as those in ordinary use in this class of stoves. Hence a detailed description thereof is not thought to be necessary in this place. To the upper end of the said feed-pipe is secured a gas-generator, B, in open communication with the needle-valve chamber C by a conduit, D, and pipe E, forming a passage-way from the generator to the needle-valve chamber. Above the generator (and an integral part of the same) is a funnel-shape base, F. Said base, 35 40 together with the perforated rim G, forms the exterior wall or shell of the combustion-chamber. Around the inner edge of the base F is formed a rabbet adapted to receive the lower edge of the ring G to prevent its lateral displacement from the base. Said ring and the base may be cast in one piece instead of being in two parts, as shown in the drawings. In the side of said base is a hole, in which is inserted a tube, H, which terminates about midway in 45 50 the combustion-chamber and extends out therefrom in alignment with the needle-valve cham-

ber C, as shown in Fig. 1. Said tube H is secured in place by a set-screw, a; or the tube may be screwed therein. A set screw, however, is preferred.

I is a cover fitting closely the top of the ring, as seen in Fig. 2. To the under side of the cover is attached, by hangers b, a cylinder, J, a detached view of which is shown in Fig. 3. It will be observed that the lower end of the cylinder is close to the bottom of the base F, but not so close as to touch, whereas the upper end is not close to the cover, there being a considerable space between the end of the cylinder and the cover. It will also be observed that there is an annular space between the cylinder and the wall of the combustion-chamber, and that the tube H terminates in the said cylinder, there being an opening in the side of the cylinder for the tube H to pass loosely through.

K is an oil-cup secured to the supply-pipe A by a set-screw, c. The purpose of the said cup will presently be shown.

The practical operation of the burner is as follows: In order to start the burner a small quantity of oil is turned into the cup K from the base F of the combustion-chamber, which oil is injected therein from the needle-valve chamber. On opening the valve e for that purpose said chamber is filled with oil from the supply-pipe A, which flows therefrom into the generator, thence into the needle-valve chamber, from which it is injected through the tube H into the combustion-chamber, or the cylinder J therein, under the end of which it runs into the chamber sufficiently to start the burner on ignition. The oil flows from the combustion-chamber or base F through an orifice, d, Fig. 4, and falls upon the conduit or extension D of the generator, and runs from the point d' into the cup. The oil is prevented from running down the outside of the generator B and leaking between the collar D' of the catch-cup and the feed-pipe by a flange, a', projecting from the sides of the conduit. Said flange is of no use, provided the collar D' is fitted tightly around the feed-pipe. The oil in the cup, when ignited, heats the generator and the conduit D, the conduit being heated by the burning oil in the extension K' of the cup. The gas thus generated passes from the generator into the needle-valve chamber, from whence it escapes on open-

ing the needle-valve *e* into the tube *H* and discharges in the cylinder *J*. The gas passes up in the cylinder and flows over the upper end thereof into the annular space *N*, from which it issues through the perforations of the ring *G* in jets of bright blue flames. The heat of the jets is conveyed down to the generator by the sides of the base *F* of the combustion-chamber, and continued in and about the generator for vaporizing the oil therein when the oil in the cup is burned out. The quantity of oil supplied to the generator is regulated by a valve in the supply-pipe, (not shown in the drawings,) and of which valve *A'* is the stem. The volume of gas admitted to the combustion-chamber is regulated by the needle-valve, of which *C'* is the stem.

The lines *C''* indicate a hood covering the point of the needle-valve and the end of the tube *H* to prevent drafts of air from flickering the flow of gas from the needle-valve to said tube *H*. Said hood is more clearly shown in Fig. 4.

What we claim as our invention, and desire to secure by Letters Patent, is—

1. In vapor-burners, the cover *I*, and depending therefrom a cylinder with open ends, the lower end of which terminates near the bottom of the base *F* of the combustion-chamber and the opposite end terminating in the upper part

of the said chamber, and perforated ring *G*, in combination with the said base and horizontal induction-pipe, substantially as described, and for the purpose set forth.

2. In vapor-burners for gasoline-stoves, the base of the combustion-chamber provided with an orifice for the emission of oil to the heating-cup flange *a'* and point for conducting the oil into the heating-cup, substantially as described, and for the purpose set forth.

3. The induction-pipe *H*, inserted in the side of the combustion-chamber and terminating in a cylinder therein, and arranged in relation to and in combination with a needle-valve mechanism, substantially as set forth, and for the purpose specified.

4. The combination of the perforated ring *G*, the cup and depending cylinder, the base *F*, having the orifice *d*, the horizontal induction-pipe, and the conduit provided with a collar and point, substantially as and for the purpose set forth.

In testimony whereof we affix our signatures in presence of two witnesses.

PAUL SCHNEIDER.
HENRY TRENKAMP.
